[57] **CLAIM**

The ornamental design for a battery powered grease gun, substantially as shown and described.

DESCRIPTION

FIG. 1 is a perspective view of a battery powered grease gun showing our new design;

FIG. 2 is a bottom plan view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a front elevational view thereof with a portion of the gun barrel broken away for convenience of illustration.

The nozzle shown in FIG. 1 has been omitted from FIGS. 3 through 7 for convenience of illustration.

FIG. 3

FIG. 4

FIG. 1

FIG. 5

FIG. 7

FIG. 2

FIG. 6
